Inventor

Vernon E. Walters

By Mackenzie, Spencer & Eliot.

Attorney

UNITED STATES PATENT OFFICE.

VERNON E. WALTERS, OF DETROIT, MICHIGAN, ASSIGNOR TO GENERAL MOTORS CORPORATION, OF DETROIT, MICHIGAN, A CORPORATION OF DELAWARE.

JIG.

Application filed July 16, 1921. Serial No. 485,322.

The present invention has reference to jigs and more particularly to the latch and operating handle for the movable member thereof.

5 In quantity production, it is necessary in each operation that the operator perform his work with as few movements as possible. The elimination of a single extra movement by an operator in operating a 10 machine that turns out thousands of articles every day will materially speed up the production of that article.

In jigs employing latches for holding the bushing plate in operative position as usually constructed, it is necessary for the operator to perform two movements in raising the bushing plate to remove the work—one to release the latch and one to raise the plate. One of the objects of this invention 20 is the provision of a device whereby one of these movements may be eliminated. In other words, one of the objects of this invention is the provision of a combined latch and operating means whereby the latch may 25 be released and the movable member operated with a single movement of the operating handle.

Another object of the invention is the provision of an improved arrangement of the 30 means for automatically operating the latch.

Other and further objects and advantages of the invention will appear as the description proceeds.

On the drawing:

35 Figure 1 is a side elevation of the device with parts in section and parts broken away;

Figure 2 is a top plan view thereof, and

Figure 3 is a perspective view of a detail thereof.

40 On the drawing, the reference numeral 5 indicates a base plate which is provided with supports 6 and 7 which may be of any suitable construction and which are shown on the drawing as being integral with the plate 5. The base plate 5 is provided at the ends thereof with upwardly extending projections 8 and 9.

Suitable means are provided for holding the work while it is being operated upon.

50 In the form of the device shown on the drawings, the work or article is held in position to be operated upon by means of a locating block without the aid of clamping mecha-

nism. It is understood, however, that clamps or other securing means may be employed if required, or desirable. The locating block 10 for supporting the work to be operated upon is secured to the upper side of the plate 5 between the uprights 8 and 9 by means of suitable fastening means such as the pins or screws 11 and 12. The locating block is provided with an aperture 13 in which is adapted to be removably mounted the reduced end of a positioning pin 14. The positioning pin 14 is provided with a 65 collar 15 which engages about the edge of the aperture 13 and limits the downward movement of said pin. The pin is provided with an upwardly extending portion 16 which is adapted to engage in a corresponding opening 17 in the work or article 18 that is to be operated upon.

The locating block 10 may be of any suitable form and is so made that it will locate and hold the article in proper position 75 to be operated upon. The one shown is adapted to be used in connection with the special form of article 18 shown in Fig. 1. This article has a plain horizontal surface 19 and a plane vertical surface 20 which are 80 adapted to engage the corresponding faces on one of the projections 21 on the block 10. It will thus be seen that the work or article 18 is held in position to be operated upon by the projections 21 and the positioning pin 14. 85

The upright 8 is provided at its upper end with the reduced portion 22 to which is pivoted the bifurcated end of a bushing plate 23. The free end of the bushing plate is provided with a slot 24 in which 90 is pivotally mounted the latch 25. The latch 25 has a depending portion 26 which is provided with a lip 27 that is adapted to engage a keeper 28 removably secured in the upright 9. The lip 27 of the latch 26 is 95 provided with a beveled surface 29 which is adapted to engage the corresponding inclined surface 30 on the keeper 28 to automatically operate the latch when the bushing plate is moved to lowered position. The 100 latch 25 is also provided with a projection 31 which extends laterally over a recess 32 in the upper surface of the bushing plate 23.

Resilient means is provided for engaging the projection 31 to operate the latch in one 105 direction. As shown on the drawing, this

means consists of a spring 33 seated in the recess 32. In order to prevent dirt, grease, and particles of metal from entering the recess 32 and interfering with the operation of the spring a housing 34 for the upper end of the spring 33 is provided. This housing is slidably mounted in the recess and its upper end is adapted to engage beneath the projection 31.

10 The plate 23 may be provided with any desired number of suitable guides for the operating tools. Where the operation is that of drilling or boring, as indicated in Fig. 1, the guides may be in the form of bushings 35 which are removably mounted in suitable holes in the bushing plate 23.

15 Rigidly attached to the latch 25 and extending forwardly therefrom is a handle 36 for operating the latch and for elevating the bushing plate 23.

20 In the operation of the device, the work or article 18 to be operated upon is placed in position on the locating block 10 with the pin 14 engaging the recess 16. On lowering 25 the bushing plate the latch 25 will automatically engage the keeper 28. After the operation has been performed on the article 18, that is, after the recesses 37 have been bored or drilled therein, as shown in Fig. 1, 30 the latch 25 may be released and the plate 23 elevated in one movement of the handle 36 by the operator.

25 In other words, when the operation is complete, it is only necessary for the operator to perform a single movement of the handle 36 in order to release the latch and elevate the bushing plate, after which the work or article 18 may be removed and another placed in position on the block 10.

30 It is thought from the foregoing taken in connection with the accompanying drawings that the construction and operation of my device will be apparent to those skilled in the art; and that various changes in size, 35 shape, and proportion and details of construction may be made without departing

from the spirit and scope of the appended claims.

What I claim is:

1. A work-holding device comprising two 50 members, one of which is provided with tool guiding means, said members being hingedly connected on one side of the tool guiding means, and means for retaining said members in work-holding relation including 55 a keeper on one member, a latch pivoted to the other member, spring means acting upon said latch and operative to force the latch into engagement with the keeper, and a handle for said latch whereby the latch may 60 be disengaged in opposition to the action of said spring means and said members may be separated.

2. In a jig of the class described, a stationary member, a tool guiding member hinged thereto, a keeper on said stationary member, a latch on said tool guiding member having a depending portion for engaging said keeper and a projection extending along said movable member, a spring seated in said 70 movable member and provided with a movable housing for protecting said spring and for engaging said projection to retain said latch in engagement with said keeper, and a handle for operating said latch and for 75 moving said movable member, substantially as shown and described.

3. In a jig of the class described, a stationary member, a tool guiding member hinged thereto and provided with a recess, 80 a keeper, a latch pivotally connected to said tool guiding member for engaging said keeper, said latch having a projection extending across said recess, a spring seated 85 within said recess, a housing for the outer end of said spring slidably mounted in said recess, and engaging said projection, substantially as shown and described.

In testimony whereof I affix my signature.

VERNON E. WALTERS.
